CONFECTION FREEZER

Chester Manfield Fitzgibbon, Milwaukee, Wis.

Application November 8, 1949, Serial No. 126,165

5 Claims. (Cl. 259—81)

1

This invention relates to an improved electric motor driven freezer of the type adapted to be used in a domestic mechanical refrigerator to freeze confections such as ice cream, the primary object of the invention being to provide a more efficient and practical device of this kind composed of a minimum number of simple parts which can be easily assembled and disassembled for cleaning or repairs, and capable of being made in an attractive and serviceable form at relatively low cost.

Other important objects and advantageous features of the invention will be apparent from the following description and the accompanying drawings, wherein, merely for purposes of illustration, a specific embodiment of the invention is set forth in detail.

In the drawings:

Figure 1 is a top plan view;

Figure 2 is a side elevation;

Figure 3 is a right-hand end elevation of Figure 2;

Figure 4 is a vertical longitudinal section taken on the line 4—4 of Figure 3;

Figure 5 is a plan view of the drum container removed from the frame or base and partly in section, and with a cap cover removed and shown in dotted lines;

Figure 6 is a transverse vertical section taken on the line 6—6 of Figure 2.

Referring in detail to the drawings, wherein like numerals designate like parts throughout the several views, the illustrated device comprises a base or frame 7 in the general form of a rectangular refrigerator tray having a bottom 8, longitudinal side walls 9, 9, and an end wall 10, the upper edges of the side walls 9 and side walls 10 being on the same level and provided with a bead 11. The tray 7 has another end wall 12 which has a semicircular cutout portion 13. At each side of the end wall 12 the side walls 9 have inwardly projecting flanges 14 at their upper edges.

A motor support plate or base 15 has ears 16 at the opposite ends to rest upon the flanges 14 and wing bolts 17 traverse the ears and flanges to secure the motor base removably in place. The motor base 15 is concaved intermediate its ends to fit the cutout portion 13 and provide a portion 18 secured to and contoured to conform to the under side of the casing of a small electric motor 19 having a squared shaft end 20 projecting from the motor casing toward the opposite end of the tray and parallel to the bottom 8 thereof, as shown in Figure 4. An appliance cord 21 extends

2

from the motor 19 for connection to a suitable source of current preferably an outlet within the refrigerator (not shown). The motor shaft end 20 is axially aligned with a bearing hole 22 provided in the upper part of the tray end wall 10.

The container drum, generally designated 23, comprises a hollow cylinder 24 having an end closure 25 having a centered recess 26 opening at its inner side. The outside of the cylinder 24 adjacent the end closure 25 is threaded, as indicated at 27, to provide for removable attachment thereto of the cap 28 which has a centered pintle 29 to project through and turn in the bearing hole 22 in the tray end wall 10 when the drum 23 is in place in the tray 7. When the drum is removed from the tray 7, as on completion of a confection freezing operation, the cap 28 can be removed from the closed end of the drum and threaded on the external threads 30 on the open opposite end 31 of the cylinder 24, the open end 31 being closed during operation of the device by the cover cap 32.

The cover cap 32 has a central boss 33 having a squared socket 34 into which the squared motor shaft end 20 is fitted to support the adjacent end of the drum 23 and form a drive connection between the motor and the drum. The shaft end 20 is optionally permanently or removably fitted in the socket 34. The boss 33 has another socket 35 in the inner end.

An agitator or paddle assembly, generally designated 36, is not driven by the motor 19, but fits snugly and removably within the drum cylinder 24. The paddle assembly 36 comprises a rectangular frame composed of longitudinal side members 37, 37 connected at their ends by end members 38, 38, each having an outwardly projecting pin 39 centered thereon for engaging in the recess 26 in the drum end closure 25 and in the socket 35 in the cover cap boss 33, whereby the assembly is secured against endwise movement in the cylinder and the paddle frame and members 38 are spaced inwardly from the ends of the cylinder 24. The paddle assembly 36 further comprises a longitudinally paddle bar 39 connected to and extending between the midpoints of the end members 38. Extending from the bar 39 in the plane of the end members 38 are spaced pairs of diametrically opposed short paddle fingers 40, 40 and a pair of intermediate longer paddle fingers 41, 41. The fluid from which the desired confection is frozen beats against the paddle assembly 36 as the drum 23 is rotated, whereby the fluid is adequately agitated. The paddle assembly can be removed from

the cylinder 24 after removal of the cover cap 32 simply by pulling it out of place.

Upon starting the motor 19, the drum 23 rotates on its axis within the tray base or frame 7 whereby the contents of the cylinder 24 are rotated and agitated until the motor is stopped by disconnecting the same from its current source.

The above-described device, being of the general form of a conventional mechanical refrigerator ice cube freezing tray, can be readily substituted for such a tray in the freezing compartment of the refrigerator and the freezing of the confection, such as ice cream, accomplished without interruption to the usual functioning of the refrigerator and without disturbing the contents thereof.

What is claimed is:

1. A confection freezer comprising an elongated tray having a first end wall having a centered journal bearing thereon and a second end wall and side walls, a motor having a shaft end, means mounting said motor on said tray between said side walls at said second end wall with said shaft end axially aligned with said journal bearing on said first end wall, a confection containing drum comprising a tubular cylinder having an open end and a closed end, means on said closed end having an axial pintle journaled in said journal bearing, a removable cover cap closing the open end of said cylinder, and means supportably and non-rotatably connecting said cover cap axially to said motor shaft end, the first-mentioned means comprising a pintle cap removably mounted on the closed end of said cylinder, the second-mentioned means being disconnectable and said pintle being disconnectable from said journal bearing to free said drum for removal from said cover cap and from said tray, said pintle cap being removable from the closed end of said cylinder for transfer to close the open end of said cylinder upon removal of said cylinder from said cover cap and from said tray.

2. A confection freezer comprising an elongated tray having a first end wall having a journal bearing thereon and a second end wall and side walls, a motor having a shaft end, means mounting said motor on said tray between said side walls near said second end wall with said shaft end axially aligned with said journal bearing on said first end wall, a drum having a first end having an axial pintle journaled in said journal bearing and a second end, and means axially securing said second drum end to said motor shaft end whereby said drum is axially rotated in said tray when said motor is operated, a stationary paddle assembly within said drum and otherwise unconnected with said motor shaft end, said drum ends having axial sockets therein, said paddle assembly comprising a frame removably fitting within said drum having pins on its opposite ends engageable with said sockets whereby said assembly is centered in said drum and prevented from moving endwise relative to said drum.

3. A confection freezer comprising a horizontally elongated tray having first and second end walls and sidewalls, a motor mounted protectively within said tray adjacent to said first end wall, said motor having a horizontal shaft projecting toward said second end wall, said second end wall having a journal bearing axially

aligned with said motor shaft, a horizontally elongated drum positioned between said sidewalls within said tray with its sides protected by said sidewalls from lateral contact by outside objects, a pintle on the end of said drum adjacent to said second end wall and supportably engaging said journal bearing, and socket means on the other end of said drum supportably and non-rotatably receiving said motor shaft whereby said drum is rotated on its axis when said motor is operated; said pintle being disengageable from said journal bearing and said motor shaft being disengageable from said socket means by endwise movement of said drum in the direction of said first end wall to permit removal of the drum from said tray and means removably mounting said motor on said tray whereby said motor can be removed from said tray to permit said drum to be moved sufficiently toward said first end wall to effect removal of said drum from said tray.

4. A confection freezer comprising a tray including a pair of spaced end walls, a motor having a rotatable shaft end arranged above and adjacent one of said end walls with the shaft end facing the other end wall of said tray and fixedly supported on said one end wall, a drum having one end open and the other end closed positioned within said tray with the open end facing toward the shaft end of said motor and spaced from said shaft end, a cover cap positioned between the shaft end of said motor and the open end of said drum and threadedly secured to the open end of said drum and connected to said shaft end for rotation therewith, and a cap rotatably supported on the other end wall of said tray and embracingly secured to the closed end of said drum.

5. A confection freezer comprising a tray including a pair of spaced end walls, a motor having a rotatable shaft end arranged above and adjacent one of said end walls with the shaft end facing the other end wall of said tray and fixedly supported on said one end wall, a drum having one end open and the other end closed positioned within said tray with the open end facing toward the shaft end of said motor and spaced from said shaft end, a cover cap positioned between the shaft end of said motor and the open end of said drum and threadedly secured to the open end of said drum, means on said cap and engaging said motor shaft end for connecting said cover cap for rotation with said shaft end and a cap rotatably supported on the other end wall of said tray and embracingly secured to the closed end of said drum.

CHESTER MANFIELD FITZGIBBON.
